(57) **CLAIM**

The ornamental design for a hook plate, as shown and described.

DESCRIPTION

FIG. 1 is a front perspective view of the hook plate comprising the new design;

FIG. 2 is a bottom perspective view of the design of FIG. 1;

FIG. 3 is a top view of the design of FIG. 1;

FIG. 4 is a bottom view of the design of FIG. 1;

FIG. 5 is a right side elevational view of the design of FIG. 1;

FIG. 6 is a left side elevational view of the design of FIG. 1;

FIG. 7 is a front elevational view of the design of FIG. 1; and

FIG. 8 is a back elevational view of the design of FIG. 1.

FIG. 9 is a front perspective view of an alternative embodiment of the hook plate of FIG. 1;

FIG. 10 is a bottom perspective view of the design of FIG. 9;

FIG. 11 is a top view of the design of FIG. 9;

FIG. 12 is a bottom view of the design of FIG. 9;

FIG. 13 is a right side elevational view of the design of FIG. 9;

FIG. 14 is a left side elevational view of the design of FIG. 9;

FIG. 15 is a front elevational view of the design of FIG. 9; and,

FIG. 16 is a back elevational view of the design of FIG. 9. The broken lines shown in the figures are directed to the environment and are for illustrative purposes only; the broken lines form no part of the claimed hook plate invention.

The relatively light uneven broken lines shown in the figures represent contour, not surface decoration.
